METHOD FOR THE MANUFACTURE OF
CONSTRUCTION COLUMNSWarren A. Krane, San Francisco, Calif., assignor
to Cement Wrapped Pipe Company, Ltd., San
Francisco, Calif., a corporation of Arizona

Application January 13, 1934, Serial No. 706,503

3 Claims. (Cl. 25—154)

This invention relates generally to methods and machines for the manufacture of construction columns, particularly those employed in piers or abutments and which are commonly known as 5 piles.

It is a general object of the invention to provide a method for the manufacture of an armored pile of the character disclosed and claimed in my co-pending Patent No. 1,950,801, granted 10 March 13, 1934. The pile disclosed in said co-pending application is provided with a grooved core surrounded by a reinforced jacket of concrete. The present invention makes it possible to form such a jacket in a minimum of time and 15 at a cost basis enabling commercial production.

Further objects of the invention will appear from the following description in which the preferred embodiment of the invention has been 20 set forth in detail in conjunction with the accompanying drawings.

Referring to the drawings:

Figure 1 is a side elevational view, in cross-section, illustrating the more essential parts of 25 my machine and its application in the manufacture of concrete jacketed piles.

Figure 2 is a cross-sectional detail taken along the line 2—2 of Figure 1.

Figure 3 is a cross-sectional detail, taken along 30 the line 3—3 of Figure 1.

Figure 4 is a plan view, illustrating the manner in which the concrete and reinforcement are supplied to the rotating form in carrying out 35 my invention.

Figure 5 is a side elevational view, partly in cross-section, showing a concrete jacketed pile manufactured in accordance with my method.

Both the method and the machine disclosed herein have been generically disclosed and claimed 40 in my co-pending application Serial No. 675,659, filed June 14, 1933, particularly with respect to the supplying of a concrete jacket for steel pipes and conduits. In the present invention modifications have been made, to facilitate manufacture 45 of a concrete jacketed pile of the character referred to above.

Referring to Figure 5, there is shown a pile or construction column of the character which I desire to manufacture by my method and my machine. This pile consists of a core 10, formed of 50 suitable material such as wood, the periphery of which is provided with a continuous groove 11 of helicoidal form. Surrounding the core there is a jacket 12 of concrete which is provided with a metallic reinforcement 13. Covering the con-

crete there is a surfacing 14 of cloth or like material. Although the concrete jacket affords a smooth exterior, it will be noted that the concrete fills the helicoidal groove 11, so as to afford a good interlock between the jacket and the core. 5 This interlock not only serves to properly distribute stresses between the jacket and the core, but also serves as a labyrinth seal to prevent seepage between the jacket and the core.

Referring now to Figures 1 to 3 inclusive, the principal parts of the machine which are utilized consist of a guide structure 16 over which the plastic concrete mixed is conveyed for its application to the wood core 10. With reference to the detailed construction illustrated, the guide 15 structure is formed by a channel 17, having its flat back uppermost. In order to operatively support channel 17, a plate 18 underlies its intermediate portion and has its edges secured to the depending side flanges 19. A stirrup 21 underlies plate 18, and these parts are pivotally connected together by means of a bolt or pin 22. Such a pivotal connection permits swinging of the channel 17 about a generally upright axis. Stirrup 21 is in turn pivotally connected upon a 20 horizontal axis with a yoke 23. This latter connection is formed by the pivot pins or journals 24, between stirrup 21 and the side upright members 26 of the yoke 23. The attachment between the side upright members 26 and the main portion of the yoke 23 is preferably adjustable, as by means of bolts 27 which can be engaged in any one of several apertures in the upright members 26. Yoke 23 is in turn carried by a frame 28 25 which forms a part of a movable carriage. It may be explained at this point that in operating the machine core 10 is mounted upon suitable 30 centers for rotation upon its axis. The carriage, of which frame 28 is a part, is adapted to be moved longitudinally of the axis of rotation of core 10, at a suitably synchronized rate.

It is evident from the above description that the support for channel 21 permits universal movement of this channel with respect to the core 10. In other words, this channel can be swung 45 about a generally upright axis at various angles with respect to the axis of rotation of the core, or can be tilted at various angles with respect to the horizontal.

In order to provide means for feeding a layer 50 of plastic material upon the upper surface of the channel 17, I provide a hopper 31 which can be made of sheet metal plates welded together. This hopper overlies channel 17 and is preferably positioned substantially co-axially with the 55

axis of pivot pin 22, so that varying amounts of material within the hopper have substantially no effect upon counterbalancing of the channel. It is desirable to retain hopper 31 in its operating position by a hinge connection, so that it can be unlocked and swung to one side. Thus, one side of the hopper has been shown connected to one side of the channel 17 by hinge structure 32. The other side of the hopper is adapted to be retained in operating position by releasable locking means which may be formed as follows:—A rod 33 has a pivotal connection 34 with one side of the channel 17. A collar 36 is slidably positioned upon rod 34 and is urged toward the pivotal connection 35 by compression spring 37. Mounted upon the corresponding side of hopper 31, there is a bracket 39, having a lower flange 40 which is slotted to receive rod 34. Upon rod 34 swinging outwardly and downwardly, collar 36 is freed with respect to flange 40, to permit the hopper to be swung to one side about the axis of hinge structure 32. When the hopper is returned to its normal position, rod 34 can be swung upwardly to again engage collar 36 above the slotted flange 40. In this connection it will be noted that the surfaces of collar 36 are so formed as to permit automatic engagement of the collar with the upper surface of flange 40, when the rod 34 is swung upwardly.

30 Certain parts of the hopper 31 serve to determine the thickness of the coating applied to the pipe. Therefore, it is desirable to have this hopper occupy a predetermined position with respect to the channel 17 when it is in operating position. For this reason, spacer elements 42 have been shown interposed between the lower side edges of the hopper 31 and the side edge portions of channel 17. The hopper rests upon these spacer bars or elements when in normal operating position as shown in Figure 1. Plastic material supplied to hopper 31 is fed forwardly over channel 17, towards the pipe to be coated. A smooth surface for the upper side of the channel can be secured by a sheet metal surfacing 44. 45 In order to prevent any flow of plastic material in the reverse direction—that is, underneath the rear lower edge of the hopper—the rear hopper wall 45 is provided with an adjustable gate 46. The lower edge of gate 46 can be adjusted to be 50 in close proximity with the sheet metal surfacing 44 of channel 17, to permit passage of a strip of foraminous reinforcement, but to prevent extrusion of plastic material.

To provide for the feeding of plastic material from the hopper in a direction towards the core, a plate 47 is removably secured to the forward hopper wall 49. The lower portion of plate 47 is provided with a forwardly curved lip portion 50 which overlies the upper surfacing 44 of the 60 channel 17.

Referring to Figure 2, it will be noted that the intermediate part 50a of the lip 50 is offset upwardly with respect to the side parts 50b. As will be presently explained, this is for the purpose of supplying the layer of plastic material with a distinct intermediate ridge for filling the groove -- in the core 10.

In order to secure a uniform and continuous flow of plastic hydraulic Portland cement mortar 70 from hopper 31, below the lip portion 50, I provide means to subject certain parts to continuous and rapid vibration. Thus, mounted upon the forward wall 49 of the hopper 31, by way of a bracket 52, there is a pneumatic hammer 53. 75 The operating plunger 54 of this hammer rests

upon a bar 56 which in turn engages the lip portion 50. Since lip portion 50 is somewhat resilient and has its side edges free with respect to the hopper, it is vibrated in a generally vertical direction to insure a smooth, continuous flow of plastic material. In addition, the main part of the hopper 31, and particularly the rear wall 45, is subjected to continuous vibration by means of a pneumatic hammer 57.

During its movement from the hopper to the core 10, the layer of plastic material fed from the hopper is conveyed along by a strip of foraminous metal reinforcement, such as wire screening 58. As is evidenced from Figure 1, this strip of reinforcement passes beneath the lower edge of 15 gate 46, and is therefore substantially flat upon the upper surfacing 44 as it passes beneath the hopper towards the core. This reinforcement is supplied from a suitable source, such as a reel, and is preferably placed under tension and flat-tened before it passes beneath hopper 31. Thus, in Figure 1 the reinforcing strip 58 is shown passed beneath a roller 59 fixed to the side bracket 61. From roller 59 the reinforcement passes over roller 62 and fixed roller 63, before it passes beneath hopper 31. Rollers 62 and 63 are carried by the side brackets 64, and roller 62 is adjustable as by means of hand screws 66.

It will be noted in Figure 1 that channel 17 terminates short of the core 10, and that immediately underlying the core there is an extension plate 68. The upper surface of this plate is substantially co-planar with the upper surfacing 44 of the channel 17, and interposed between the forward end edge of channel 17, on the adjacent edge of plate 68, there is a lateral slot 69. Plate 68 is fixed to side structural members 71 which in turn are secured to the side flanges 19 of channel 17. Plate 68 is preferably vibrated rapidly in a vertical direction, and for this purpose there is shown a pneumatic hammer 72 mounted upon the structure members 71 beneath the plate 68. The operating plunger 73 for this hammer engages a cross-bar 74 which in turn engages the under side of plate 68. In order to confine the layer of plastic material during its movement from hopper 31 to plate 68, side guide strips 76 are mounted upon the edge portions of channel 17.

During operation of the machine it is desirable to have plate 68 yieldably urged upwardly against the lower side of the core, but under varying conditions of operation it is also desirable to adjust the amount of this force. To enable such adjustment there is shown a cross-bar 77 secured to structural members 71, and upon which various counterbalancing weights 78 can be disposed. An increased amount of weight applied to cross-bar 77 tends to reduce the force normally urging plate 68 upwardly against the lower side of the core.

Simultaneously with the application of plastic material and foraminous reinforcement to the pipe, it is desirable to apply an outer surfacing material. Good results have been secured by utilizing ordinary cotton cheesecloth, although paper can be employed if desired. Thus, referring to Figure 1, there is shown a strip 81 of cheesecloth which is supplied from a suitable reel. As this strip comes from the supply reel 70 it is passed between a pair of parallel bars 82, to remove wrinkles and the like. From bars 82 the strip passes over a guide plate 83 which is carried upon the under side of channel 17. Upon leaving the forward end of guide plate 83, the cloth 75

strip is passed over a roller 84, and from thence is passed upwardly through slot 69 to the upper side of plate 68.

For supporting certain parts of the machine, as for example the cloth and reinforcement supply reels, a pair of upright structural members 86 are indicated, near the rear end of the channel 17 and on opposite sides thereof. These upright members are generally adjustable with respect to the carriage for the machine, and the sides of the channel may be provided with rollers for engaging their inner edges, thus generally limiting swinging of the channel 17 about a vertical axis.

Operation of the machine described above, in carrying out my method, can be reviewed as follows: The machine is initially set up and adjusted to secure the thickness of coating desired upon the core, and to insure proper operation consistent with the diameter of the core being coated and the pitch of groove 11. Assuming the machine has been properly adjusted for operation, a proper plastic mix, consisting, for example, of Portland cement mortar, is introduced into the hopper 31, and the ends of the foraminous and cloth strips are attached to one end of the core or to a center constituting an extension of one end of the core. The various pneumatic vibrators and hammers are now put into operation, and rotation of the core is commenced, with simultaneous synchronized movement of the carriage supporting the channel 17, longitudinally of the core. As the strip of foraminous reinforcement progresses beneath hopper 31, a layer of the plastic mix is applied to the same, for substantially the full width of the reinforcement, and this layer, having a cross-sectional contour, substantially as shown in Figure 2, is then conveyed, together with the reinforcement, towards the core. As the reinforcement progresses over plate 68, the cloth strip 81 is applied to the under side of the same, to be simultaneously wrapped upon the core together with the plastic material. In a proper synchronized operation, the ridge formed by the offset of part 50a of the graduated lip 50 meshes with a helicoidal groove 11 in the core, thus furnishing sufficient plastic material to substantially fill the same. Because of the tension supplied to the reinforcement as it is applied to the core, and because of repeated pounding or vibratory movement of plate 68, the reinforcement embeds itself to an intermediate depth in the layer of plastic material. Referring to Fig-

ure 4, it will be noted that the angle of advance of the layer of plastic material with respect to the core, and the width of the layer, are such that one edge portion of the plastic layer as it is being supplied overlaps with an edge portion of a preceding convolution. This serves to overlap the edges of successive convolutions of the reinforcement, as shown in Figure 5, and also serves to ensure a good bond between adjacent edges of successive convolutions. It will also be noted that the cloth strip 81, as shown in Figure 4, is offset with respect to the layer of plastic material. This results in one edge portion of the layer of plastic material being exposed for forming proper junctions, and also causes the surfacing to be overlapped, as shown in Figure 5.

In some instances it may be desirable to provide a jacket of greater thickness than that shown in Figure 5. In such event the cloth surfacing is stripped off the first layer of concrete, after the concrete has set, and then a second layer of plastic material of even thickness is applied upon top of the first coating, preferably by wrapping in the reverse direction.

I claim:

1. In a method for applying a coating of plastic material to a core provided with a helicoidal groove in its periphery, the steps of applying a layer of plastic material helicoidally upon the core at a pitch corresponding to the pitch of the groove, the layer having a portion of increased thickness to substantially fill the groove.

2. In a method for applying a coating of plastic material to a form, the form being provided with a helicoidal groove in its periphery, the steps of applying a layer of plastic material helicoidally upon the core at a pitch corresponding to the pitch of the groove, the layer having an intermediate portion of increased thickness to substantially fill the groove.

3. In a method for applying a coating of plastic material to a core provided with a helicoidal groove in its periphery, the steps of applying a layer of plastic material helicoidally upon the core at a pitch corresponding to the pitch of the groove, and simultaneously applying a foraminous reinforcement in such a manner that the reinforcement is embedded in the layer of plastic material, the layer as it is being supplied having a portion of increased thickness to substantially fill the groove.

WARREN A. KRANER.
